INVENTOR

J. A. Belt

UNITED STATES PATENT OFFICE.

JOHN A. BELT, OF TORONTO, ONTARIO, CANADA.

CENTRIFUGAL LIQUID-EVACUATOR.

1,395,218.

Specification of Letters Patent. Patented Oct. 25, 1921.

Application filed March 3, 1917, Serial No. 152,446. Renewed September 19, 1921. Serial No. 501,830.

To all whom it may concern:

Be it known that I, JOHN ANDREW BELT, a citizen of the Dominion of Canada, residing at Toronto, Province of Ontario, Dominion of Canada, having invented a new and useful Centrifugal Liquid-Evacuator for the Creation of a Vacuum Within Itself When in Operation in Liquids, do hereby declare that the following is a full, clear, 10 and exact description of the same.

My invention relates to the construction of a machine which when rapidly operated by power supplied to the driving shaft will compel the evacuation of the area within its 15 sectional and movable sides of any liquid that may have entered therein, so long as the operation is continued.

I attain this object by the mechanism illustrated in the accompanying drawings, 20 in which:—

Figure 1 represents the frame (when constructed in oblong form). Figs. 2 and 3 represent the covers of same. Fig. 4 the side cover or casing; Fig. 5 the driving shaft 25 with wheels attached; Fig. 6, the pin-hinged carriers to which the side sections are attached and carried by them; Fig. 7, represents two sections of the side. Fig. 8 presents a view of the machine complete, except part of the casing which is absent to give a partial interior view. Fig. 9 makes a similar exhibit of the machine in cylinder or drum form.

In Fig. 1, the frame comprises two similar 35 collars or sections 22, which are held firmly directly opposite each other by holding bars 33 attached to both, at the required distance. At each end of both frame collars are bearings 44 for the driving shafts; and 40 around each collar outside and within the holding bars are protecting ledges 5 which will minimize the return pressure at the ends of the side sections of liquid that has been forced out of the openings between the said 45 side sections.

Fig. 2 exhibits the cover of one of the frame collars; it fits down over it as far as the holding bars and is soldered or otherwise fastened so that their connection is 50 air-tight; it has rims with extensions 11 11 which enable it to meet the side casing all around; it has bearings for the driving shafts 44; and an opening 12 through which liquid may enter through a pipe connection 55 by gravitation or be drawn by suction produced by the operation of the machine.

Fig. 3 shows the cover for the other frame collar; it is also fastened on to same air-tight, and has a rim with extensions 11 11 to meet the side casing all around; and has 60 bearings 44 for the driving shafts.

Fig. 4 shows the side casing, which is constructed so as to meet the collar covers around the exterior of the machine and is soldered or fastened to them at its edges in 65 an air-tight manner; it has recesses to contain the holding bars, 10 10; and has an outlet 13 through which liquid from within will be forced out by the centrifugal action of the machine, and may be forced through a 70 pipe attached to said outlet.

Fig. 5 shows a driving shaft 6 with wheels attached 77. The wheels extend to the line between the ledges (55) of the frame collars, and have recesses in their rims to receive 75 the pin-hinges of the carriers (Fig. 6); one driving shaft is carried through one of the frame collar covers and has gearing 14 at its end to which power is supplied by connection with a shaft run by hand, engine, or 80 motor; and the motion thus produced will draw the pin-hinged carriers with the movable side sections around the frame collars; the other driving shaft and wheels being moved by this motion.

Fig. 6 represents a carrier, to which are attached by bolts the movable side sections; the carriers are shaped so that when pin-hinged together they will hold the side sections in the position that one edge of each 90 is a space to the inward of the nearest edge of the next section adjoining; they fit over the rims of the wheels between the recesses which receive the pinhinges; they are thus enabled to move and carry the side sections 95 around with the wheels and along the straight sides of the frame between.

Fig. 7 shows two of the side sections 99, attached to carriers as above set forth.

In Fig. 8 is exhibited a view of the machine with all parts in place, a section being removed from the casing &c to give a partial interior view; 4, bearings for driving shafts; 6, the driving shafts; 7, wheels; 9 side sections; 10 recesses in casing to contain the 100 holding bars; 11 cover rim extensions; 12, inlet pipe opening in cover; 13, outlet pipe opening in side casing; 14 cog for connection with driving power.

Fig. 9, exhibits the machine in drum or 110 cylinder form. One driving shaft 6 only is necessary; and in smaller sizes only one

2
wheel 7 is required; also there is only one bearing 4 4 in each collar 2 2 and collar cover. 5, the protecting ledges; 9 the side sections; 10 recesses holding frame holding bars; 11 cover rim extensions; 12 inlet pipe connection; 13 outlet pipe connection; 14 cog for connection of driving shaft with power supply.

The machine is operated so that the edge 10 of the side sections inclined inward will precede the rest of same; when it will perform the work, that is have the utility of, a centrifugal pump in transferring liquids.

What I do claim as my invention and desire to secure by Letters Patent is;—

1. In a device of the class described, the combination of a frame composed of two similar sections, holding bars securing said sections together, a shaft journaled in each section, a sectional side inclosing the space between the sections and adapted to be

25 moved thereabout by the shaft, an inclosing casing for the frame having an inlet opening communicating with the space between the sections and an outlet opening, and means for rotating the shaft.

2. In a device as defined in claim 1, the sectional side inclosing the space between the sections composed of slats hinged together with the edge of one slat offset with respect to the adjacent edge of the next succeeding slat.

3. In a device as defined in claim 1, wheels secured to said shaft and adapted to engage the sectional side for moving the same.

35
Toronto, Ontario, Canada, Feby. 26th, 1917.

J. A. BELT.
